(57) **CLAIM**

The ornamental design for a thermostat housing, shown and described.

DESCRIPTION

The thermostat housing is used to contain a thermostat. The thermostat may be of the type used in residential and commercial buildings.

This application is related to the following U.S. patent applications, both having the same title and both filed on the same day as this application: application Ser. No. 29/276,691, and application Ser. No. 29/276,693.

FIG. 1 is a front, right side, top perspective view of a thermostat housing showing our new design;

FIG. 2 is a top plan view thereof;

FIG. 3 is a front elevational view thereof;

FIG. 4 is a right side elevational view thereof;

FIG. 5 is a left side elevational view thereof; and,

FIG. 6 is a bottom plan view thereof.
